BY *W. H. Babcock*

ATTORNEY

UNITED STATES PATENT OFFICE.

GEORGE W. STOWE, OF NEW HAVEN, CONNECTICUT.

THILL-CO尤LING.

SPECIFICATION forming part of Letters Patent No. 317,685, dated May 12, 1885.

Application filed September 4, 1884. (No model.)

To all whom it may concern:

Be it known that I, GEORGE W. STOWE, a citizen of the United States, residing at New Haven, in the county of New Haven and State of Connecticut, have invented certain new and useful Improvements in Thill-Couplings, of which the following is a specification, reference being had therein to the accompanying drawings.

- 10 This invention relates to the anti-rattling springs employed in thill-couplings; and it consists partly in an anti-rattling spring folded into several thicknesses; partly in the combination of such a spring with a regulating-screw, which turns into and out of holes screw-tapped in said thicknesses; partly in a spring thus constructed and provided with a bend or offset for holding the middle part of the spring up out of the way of the clip; and, finally, in 15 20 a terminal flexible piece of metal attached to the anti-rattling spring and used for holding it in place, as hereinafter set forth.

In the accompanying drawings, Figure 1 represents a perspective view of my improved 25 thill-coupling. Fig. 2 represents a vertical section through the same on the central longitudinal line of the thill-iron; and Fig. 3 represents a detail view of the anti-rattling spring.

A designates the axle; B, the clip bolted to 30 the same, as usual; C, the two lugs on said clip; D, the thill-iron provided with an eye, d, which sets between said lugs; E, the pintle-bolt which passes through said eye and lugs, and F the anti-rattling spring provided with a curved 35 part, f, that bears outward against said eye. This spring is bent in the middle at g, and has its rear end provided with a thin plate, h, extending above the clip and sufficiently flexible to be bent down thereon, as shown in Fig.

1, to prevent the spring from falling through. 40 An offset, i, is formed in the rear part of the spring, just below the lugs C, to keep the bend g and proximate parts of the spring out of contact with the bottom plate, H, of said clip. In the forward part of spring F, between the 45 bend g and the curved part f, are made two folds forming three thicknesses, 1, 2, and 3, of metal.

I designates a screw which turns at will into or out of said thicknesses 1, 2, and 3, the latter being screw-tapped to receive it. The effect of this screw is to increase the stiffness of the spring by holding these thicknesses together. By screwing it out of the inner thickness 3 this effect is lessened. Said screw is 50 55 provided with a washer or bearing-plate, J, which is in contact with the external face of the spring. The additional folds increase the number of screw-threads, and thus give a better hold to the screw.

Having thus described my invention, what I claim as new, and desire to secure by Letters Patent, is—

1. An anti-rattling spring for a thill-coupling folded to form the thicknesses 1, 2, 3, for 65 the purpose set forth.
2. An anti-rattling spring for a thill-coupling provided with the stiffening-folds, in combination with a screw which takes into the thicknesses formed thereby, substantially as 70 and for the purpose set forth.

In testimony whereof I affix my signature in presence of two witnesses.

GEORGE W. STOWE.

Witnesses:

GEORGE TERRY,
J. EDWARD LUDINGTON.
